(57) **CLAIM**

The ornamental design for the transducer for tankless hot water heater as shown and described.

DESCRIPTION

FIG. 1 is a front view of a first embodiment of a transducer for tankless hot water heater showing the new design.

FIG. 2 is a perspective view thereof.

FIG. 3 is a front view of a second embodiment of a transducer for tankless hot water heater showing the new design; and,

FIG. 4 is a perspective view thereof.

The broken lines in the figures show portions of the tankless hot water heater that form no part of the claimed design.
